Atty*

UNITED STATES PATENT OFFICE.

JOHN G. DORWARD, OF ALAMEDA, CALIFORNIA.

SEALING RING.

Application filed May 6, 1922. Serial No. 559,094.

This invention relates to sealing rings and especially to an elastic type of ring whereby stationary joints may be effectively packed or sealed.

5 In reciprocating plunger pumps and like structures, it is ordinary practice when making water-tight or sealed joints to employ a tapered fit with sufficient length to take in one or more joints, or else to make one, two or more straight fits of different diameters, 10 figuring the joints to be metal to metal fit and forced into place under pressure.

Both of the above methods have proven unsatisfactory from a practical standpoint.

15 In the first place sand and grit gets into the surface of the joints and keeps the tapers from fitting properly. This causes leakage and erosion of the metal between the faces of the joints, which in time destroys the fit.

20 If the long taper is properly fitted, without any sand or grit having entered between the joints, it usually seats or locks so tight under pressure that it is almost impossible to dislodge the same or loosen the tapered joints without breaking something. On the other hand where two or more straight fits, 25 employing a metal to metal contact, are employed, they are expensive to produce and the surfaces are easily scratched or disfigured while being installed in a well. If a pump is overhauled two or three times, these joints begin to leak and they are also subject to the same damage from sand and grit as previously stated.

30 The present invention involves a novel form of sealing ring which avoids the necessity of tapering fits, straight surfaces and even close fits; the object of the invention being to generally overcome the difficulties mentioned; to improve and simplify such structures in general; to provide a ring which is Y-shaped in cross-section and constructed of rubber or like elastic material; a sealing ring which is carried by, and is removable with an interior member, and which is vertically adjustable with said member to form a seal at any point along the inner surface such as presented in a well casing or pump cylinder having a uniform 35 diameter; a sealing ring which will remain stationary when in place, and which is expansible radially, both in an outward and in an inward direction to form a seal; a sealing ring which may be stretched over 40 and then snapped into a groove to seal said groove, and which will still have a radial

outward expanding tendency when in the groove to seal the interior surface of a surrounding member. Further objects will hereinafter appear.

60

One form which my invention may assume is exemplified in the following description and illustrated in the accompanying drawings, in which—

Fig. 1 is a central vertical section partly 65 broken away of a double acting deep well pump showing various applications of the sealing ring.

Fig. 2 is an enlarged vertical section of 70 the lower end of the pump cylinder showing the seal formed between the foot valve and the cylinder.

Fig. 3 is an enlarged cross section of the sealing ring.

The sealing ring forming the subject 75 matter of the present invention is particularly adapted for sealing a joint on the interior surface of a straight bored cylinder or tube, and for sealing such a joint at any point within the cylinder or tube desired.

80

For the purpose of clearly illustrating the use of the ring, a double acting deep well pump is here shown. This pump embodies a cylinder A, a discharge casing B, from which it is suspended, an intermediate head C and a foot valve D. The pump is of the deep well type and a reciprocal movement is transmitted to the plunger 2 by means of a piston rod 3, a coupling member and guide 4, and the usual pump rods such as indicated 90 at 5. The intermediate member or head C forms a guide for the piston rod, and it also supports and guides a pair of valves 6 and 7; these valves being supported by individual annular castings 8 and 9, which 95 are connected by a threaded joint, as at 10, and supported as a unit by a tapered joint or seat generally indicated at 11. The foot valve D is similarly supported by a casting 12, which is supported by a tapered seat 13 100 and it is for the purpose of preventing leakage around the valves that the sealing rings are employed. There are three separate installations of sealing rings in this particular case and they are generally indicated at E, 105 F and G.

The sealing ring proper is perhaps best illustrated in Figs. 2 and 3. The ring is preferably constructed of rubber and is provided with a layer of cotton fabric, which is vulcanized to the exterior surface to insure stiffness and also to prevent the rubber from

110

adhering to the metal surface which comes in contact with the sealing ring when in place. The cross section of the ring is Y-shaped as shown; the inner arm of the ring indicated at 14 being shorter than the exterior arm 15 and being disposed on a greater angle than the exterior arm.

As illustrated in Fig. 1, members 8, 9 and 12, carry the sealing rings and each of these 10 members is provided with exterior annular grooves for the reception thereof. The rubber rings are stretched over and snapped into the annular grooves and will thus contract into the grooves when in register with the 15 same; the leg of the ring and the inner arm 14 forming a seal with the inner surface of the groove, and the longer or exterior arm 15 forming a contact with the interior diameter of the pump cylinder in one instance, 20 and with the interior surface of the head surface C in the other instance. The base or leg of the ring, together with the arms, are fairly elastic and are of slightly less diameter than the grooves provided for their 25 reception; therefore when stretched and in alignment with the grooves provided for their reception, contraction will be permitted and a tight fit will be formed with the grooves. The outer arm 15 of the ring will 30 flare slightly outward and will thus insure snug contact with the inner surface of the surrounding member. In other words the annular portion or arm 15 of each ring will, due to the flare provided, become slightly 35 compressed when inserted in the cylinder or other member provided for its reception, and will therefore press tightly and snugly against the surrounding surface of said member and automatically form a seal or 40 joint. When water pressure is applied, the pressure on the surface of the exposed portion of the ring will press the outer portion 15, and also the inner portion 14, thus further increasing the sealing action.

45 The rings as designed require comparatively little space and require no mechanical clamping devices or expanding members to hold them into position. They are at the same time sufficiently rigid and stiff, but 50 even so sufficiently elastic that if caught on any projection while being lowered into position in the pump cylinder, they will yield and pass such projections and immediately spring out to assume their natural 55 shape. This is of considerable importance when comparison is made with ordinary cup leathers, because cup leathers if used must first of all be mechanically clamped. This increases cost of operation; increases 60 the amount of space required, owing to the long heel allowed for the clamping device, and the greatest objection to cup leathers, if used for this purpose, is that they become soft and flabby when exposed to water and are inclined to flatten out. If they happen

to engage a projection while being installed in a pump, they often turn over and will not enter the cylinder, thus necessitating complete removal of the pump rods and connected parts to the surface to turn the 70 leather or install a new one. Such annoyance and cost is not encountered with the sealing ring disclosed in this application as the natural resiliency or elasticity of the material employed, and the shape of the 75 ring is such that it will positively return to normal position when released. The present ring has many other advantages when comparison is made with cup leathers or other forms of packing. First of all a seal may be made between an interior and an exterior member, particularly when no movement between said parts takes place. Such seal may be made at any point or elevation desired as long as the bore or surface encountered is uniform in diameter. The importance of this will be readily appreciated when it is considered that the interior parts, like the plunger, valves, rods, etc., are often 80 removed for inspection and repair. Several 85 of the parts are connected by screw joints and when they are assembled it often happens that the connected parts are either extended or shortened. This will make no difference in the present instance as the rings 90 G and F will make a seal whenever they come to rest; this also being true of the ring indicated at E, vertical positioning of the ring having no effect upon the sealing efficiency of the same. Secondly, the rings may 95 be quickly applied to the parts supporting the same as they are merely stretched and snapped into the grooves provided for their reception. Third, as they are in every case 100 carried by the interior or removable members, it can be seen that they may be readily removed with said members and may thus be lifted to the surface for inspection or 105 renewal. Fourth, as the rings are expandable 110 radially, both outwardly and inwardly, a mechanical seal is formed with the inner surface and the surrounding or enclosing member, said seal being further increased or tightened the moment the ring is exposed 115 to water or any other medium under pressure. Fifth, as the ring is molded, it may be manufactured at comparatively small cost, and, due to its shape, it will in all cases require a minimum of space. This is of particular importance in pumps such as here 120 illustrated as it permits material increase in the size of the valves, water flow passages, etc. The cost of machining and constructing the members carrying the sealing rings is decreased and the tapered or straight sealing joints ordinarily employed in pumps of this character can be entirely eliminated, 125 thus further decreasing the cost and accuracy of construction.

Having thus described my invention, what

I claim and desire to secure by Letters Patent is—

1. The combination with a pair of stationary cylindrical members, one mounted interiorly of the other and the interior member having an annular groove formed in its exterior surface, a rubber sealing ring adapted to be expanded to pass over the inner member and to be received by the annular groove formed therein, and a pair of annular flanges formed on said sealing ring, one flange being shorter and radially positioned with relation to the axis of the member so as to exert pressure against the face of the annular groove when in contact therewith, and a second annular flange on the ring also angularly disposed and adapted to engage the interior surface of the stationary cylindrical member and forming a seal therewith.
2. The combination of two cylindrical members, one being disposed interiorly of the other and with relation to the exterior

member, of a sealing ring supported by the interior member, said interior member having an annular seat formed therein, and a cooperating annular groove to receive the sealing ring and to support the same, said sealing ring being constructed of rubber so it may be expanded to pass over the inner member and then contracted when in alignment with the annular groove so as to enter the same, said sealing ring comprising a base portion substantially rectangular in shape and a pair of interspaced projecting annular flanges, one flange being shorter than the other and normally angularly disposed so as to exert pressure against the annular sleeve so as to form a seal therewith and placed in the annular groove and said second named flange being also angularly disposed on the exterior cylindrical member and adapted to form a seal with relation thereto.

JOHN G. DORWARD.
